US00D596056S

(12) United States Design Patent
Scheyer

(10) Patent No.: **US D596,056 S**
(45) Date of Patent: **** Jul. 14, 2009**

(54) SPIRIT LEVEL

(75) Inventor: **Wolfgang Scheyer**, Götzis (AT)

(73) Assignee: **Sola-Messwerkzeuge GmbH**, Gotzis (AT)

(**) Term: **14 Years**

(21) Appl. No.: **29/309,561**

(22) Filed: **Sep. 3, 2008**

(30) Foreign Application Priority Data

Aug. 28, 2008 (EM) 000993001

(51) LOC (9) Cl. **10-04**

(52) U.S. Cl. **D10/69**

(58) Field of Classification Search D10/69; 33/365, 366.11–366.27, 367–391

See application file for complete search history.
